DIAPER DIPPER

Paul E. Braun, 31894 Belvine Trail, Birmingham, Mich.
Filed June 11, 1959, Ser. No. 819,768
3 Claims. (Cl. 68—214)

The present invention relates to new and useful improvements in equipment used in cleansing baby diapers and more particularly to a new diaper dipper used in conjunction with a conventional toilet.

Throughout the years, the public has been subjected to the necessity of handling of soiled baby diapers. The present invention has been developed to eliminate this undesirable task.

It is therefore an object of the present invention to provide a simple, durable and inexpensive diaper dipper which is used to eliminate the undesirable and distasteful task of handling soiled baby diapers.

Another object of this invention is the provision of a diaper dipper which can be used with a conventional toilet.

Still another object of the present invention is the provision of a diaper dipper which after usage will have removed the excess liquid from the diaper.

Another object of this invention is the provision of a diaper dipper which is light in weight, while being efficient in action.

Another object of the present invention is the provision of a diaper dipper which can be used readily by a child or adult.

Another object of the present invention is the provision of a diaper dipper which will operate to engage the rim flange of a toilet bowl from either side thereby making rotation of the device 180 degrees possible.

These and other objects can be accomplished by the provision of a diaper dipper having a pair of symmetrical forked members; the tines of said forked members being in generally parallel relationship; a roller member rotatably positioned between the tines of each forked member; a flat bearing surface on each end of said roller; a structural member extending angularly upward from each forked member; a handle on each structure member in generally parallel relationship to the rollers; pivotal means on said structural members for rotatably mounting said forked members; and means for positioning the device against the rim flange of a toilet bowl during usage.

Other objects of this invention will appear in the following description and appended claims, reference being had to the accompanying drawings forming a part of this specification wherein like reference characters designate corresponding parts in the several views.

In the drawings:

FIG. 1 is a front elevation view of the diaper dipper of the present invention.

FIG. 2 is an end elevational view of FIG. 1.

FIG. 3 is a broken away cross sectional view of a modified form of the present invention in use.

Before explaining the present invention in detail, it is to be understood that the invention is not limited in its application to the details of construction and arrangements of parts illustrated in the accompanying drawings, since the invention is capable of other embodiments and of being practiced or carried out in various ways. Also, it is to be understood that the phraseology or terminology employed herein is for the purpose of description and not of limitation.

Referring to the drawings, FIG. 1 discloses a front elevational view of the diaper dipper 10 of the present invention, while FIG. 2 of the drawing discloses a side view of the device shown in FIG. 1.

2

A pair of symmetrically shaped forked members 12 and 14 have a roller supporting means on one end thereof and have a handle grip member on the other end. The handle grip member 16 is on forked member 12, while handle member 18 is on forked member 14. Intermediate the forks 12 and 14 and handles 16 and 18 are a pair of rectangular cross sectional members 22 and 24. The structural portions of course could be of any cross sectional configuration.

10 On fork member 12 and intermediate the upper end 26 and lower end 28 of the structural member 22 is an enlarged boss section 30. A portion 32 of boss 30 extends inwardly so as to form a generally flat pivotal bearing surface 34. Extending outwardly from the structural member 22 is a second boss portion 42 which is in alignment with the first mentioned boss portion 32. The remaining fork member 14 has a similar boss construction. Intermediate the upper end 36 and lower end 38 of the structural member 24 is an enlarged boss section 40. A portion 44 of boss 40 extends inwardly so as to form a generally flat second pivotal bearing surface 46. On the opposite side of the structural member 24 is a boss 48 which extends outwardly therefrom. An axial opening 50 is centrally located in both bosses 30 and 40 to receive a pivot pin 60. The pivot pin 60 is of the rivet type so as to hold both of the symmetrical forked members 12 and 14 together when the diaper dipper of the present invention is assembled.

The lower ends 28 and 38 of the structural portions 22 and 24 join the forked sections at positions to the right and left of the vertical center line of the complete assembly. The exact displacement from the centerline being dependent on the thickness of the inwardly extending boss portions 32 and 44. Because both of the forked members 12 and 14 are symmetrical, the flat pivotal bearing surfaces 34 and 46 define the vertical center line of the diaper dipper 10.

The outer portions of the forks are formed in generally parallel relationship. Fork member 12 has a triangular shaped boss 70 on the outside surface of each of the two parallel forks 72, while fork member 14 has a triangular shaped boss 80 on the outside surface of each of the other two parallel forks 82. The top surfaces thereof 74 and 84 of bosses 70 and 80 are adapted to engage the rim flange of a conventional toilet bowl (FIG. 3). While bosses 70 and 80 are shown centrally positioned, they may of course be positioned on the outside edges 76 and 86 to effect a more positive engagement with the rim flange of a toilet bowl.

50 Beneath bosses 70 and 80 are located four centrally positioned axial openings, one in each of the ends 72 and 82 of forks 12 and 14. Both openings 78 in fork 12 and 88 in fork 14 are in alignment. Intermediate the ends of the forks are positioned roller members 62 and 64. Roller 62 has a flat face bearing boss area 66 on each end thereof which engages the inside surface 90 of the fork. Roller 64 has a similar construction. A flat face bearing boss 68 is provided on both ends thereof. Rivets 94 are inserted through openings 78 and 88 to provide rotational pivots for the rollers 62 and 64. The rollers work equally well when made of solid or hollow construction.

60 FIG. 3 of the drawings shows a modified construction wherein the triangular shaped bosses 170 and 180 on the forward and rear edge surfaces 176 and 186 of the forks 112 and 114. The rollers 162 and 164 are shown in engagement with a soiled diaper 8.

Operation

70 The corner of a soiled diaper 8 is placed between the rollers 162 and 164. The diaper 8 is then placed in the toilet bowl and moved vigorously up and down to

remove the soil. When the soil is removed both of the triangular bosses 170 or 180, depending on the position of the assembly, are moved into engagement with the rim flange 6 of the toilet bowl 4. The handle grips (not shown) are drawn together to wring the diaper as it is pulled up through the rollers 162 and 164 in the direction of the arrow 100. The operation described relates to the modified form of the invention shown in FIG. 3. However, the invention shown in FIGS. 1 and 2 operates in the same manner.

From the foregoing it is apparent that the invention is simple and efficient. Manual handling of soiled diapers is held to a minimum. The device is light weight and can be effectively used by adults and children alike.

Having thus described my invention, I claim:

1. In a device for removing soil and wringing a diaper, the combination of, a pair of symmetrical forked members; the tines of the forked members being in generally parallel relationship; a roller positioned between the tines of each forked member; pivotal means for rotatably mounting said rollers; a structural member extending angularly upward from each forked member; a handle grip member on each structural member in parallel relationship with the rollers; pivotal means on said structural members to form a pair of tongs; and centrally located bosses extending outwardly from the outer surfaces of said forked tines intermediate the rollers and pivotal means for positioning said structure against the rim flange of a toilet bowl during usage.

2. In a device for removing soil and wringing a diaper, the combination of, a pair of symmetrical forked members; the tines of the forked members being in generally parallel relationship; a roller positioned between the tines of each forked member; pivotal means for rotatably mounting said rollers; a structural member extending

angularly upward from each forked member; a handle grip member on each structural member in parallel relationship to the rollers; pivotal means on said structural members to form a pair of tongs; and bosses located intermediate the rollers and pivotal means for positioning said structure against the rim flange of a toilet bowl during usage.

3. In a device for handling soiled diapers and removing said soil, the combination of, a pair of a symmetrical forked members; the tines of said forked members being in generally parallel relationship; a roller member rotatably positioned between the tines of each forked member; a flat bearing surface on each end of said roller; a structural member extending angularly upward from each forked member; a handle on each structural member in generally parallel relationship to the rollers; pivotal means on said structural members for rotatably mounting said forked members; and aligned bosses extending forwardly and rearwardly of the forward and rearward edge of the tines of said forked members intermediate the rollers and the pivotal means for positioning said device against the rim flange of a toilet bowl during usage.
